Des. 215,597
Patented Oct. 14, 1969

215,597

COMBINED CHAIR AND TELEVISION VIEWER

John W. Rich, 2117 Arden Way,
Sacramento, Calif. 95825

Filed Nov. 8, 1968, Ser. No. 14,364

Term of patent 14 years

Int. Cl. D6—01

U.S. Cl. D15—1

Fig. 1.

Fig. 2.

Fig. 3.

Fig. 4.

FIGURE 1 is a perspective view of the combined chair and television viewer;

FIGURE 2 is a side elevation of the invention;

FIGURE 3 is a bottom plan view of the invention;

FIGURE 4 is a top plan view of the invention;

FIGURE 5 is a side elevation of the invention showing the side opposite to that shown in FIGURE 2;

FIGURE 6 is a rear elevation of the invention; and

FIGURE 7 is a front elevation of the invention.

I claim:

The ornamental design for a combined chair and television viewer, as shown.
